ENGINE

Clarence E. Frank, Fraser, Mich., assignor to
 Briggs Manufacturing Company, Detroit,
 Mich., a corporation of Michigan

Application December 24, 1943, Serial No. 515,479

19 Claims. (CL 123—80)

1

This invention relates to internal combustion engines and especially to engines of the class having rotatable valves in the cylinder head providing substantial portions of the combustion space at the time of firing. In particular the present invention principally contemplates the cooling of such engines and the provision of means for controlling the expansion of portions of the cylinder head adjacent the rotatable valve so as to maintain more closely or accurately the desired operating clearances between the valve and related bearing surfaces in the cylinder head.

An object of the invention is to provide an improved internal combustion engine which may be liquid cooled in efficient manner and will be compact and relatively simple in construction as well as easy to assemble.

A further object of the invention is to provide an engine having a rotatable valve and improved means for controlling the relative expansion of the valve and cylinder head due to heating of associated portions thereof during operation.

Another object of the invention is to provide an engine having a cylinder, cylinder head and a rotatable valve in the head, such as a generally frusto-conical valve, and in which means are provided for maintaining closely predetermined operating clearances between the valve and head, especially where the valve and head are made of metals or metal alloys having different thermal expansion rates.

A still further object of the invention is to provide an improved engine of the rotatable valve type wherein the cylinder head, within which the valve is mounted, has a greater coefficient of expansion than the valve, yet provision being made in accordance with the invention to restrain any appreciable relative expansion of the head and valve at localities where it is desired to maintain substantially constant clearances between adjacent bearing surfaces of the head and valve.

A further object of the invention is to provide a cylinder head constructed for mounting and operation therein of a rotatable valve, preferably of frusto-conical shape, and in which the cylinder head is constructed in improved manner to provide efficient cooling of the valve and its associated parts as well as the exhaust conduit by means of a liquid coolant.

Another object of the invention is to provide improved means for assembling and attaching together the cylinder and cylinder head, the same being accomplished in such improved manner as to effect control of the expansion of the housing for the rotatable valve during operation, thereby

2

maintaining greater uniformity in the operating clearance between the valve and its bearing surfaces and reducing loss of lubricant due to leakage past such surfaces.

It is also an object of the invention to provide an engine having a cylinder head and a valve rotatable therein and having a different, such as a smaller, coefficient of expansion than the head and in which means is provided whereby the rate of expansion of the head will be substantially the same as the valve at certain bearing localities where it is desirable to maintain uniform operating clearances between the cooperating bearing surfaces of the valve and head.

Other objects of this invention will appear in the following description and appended claims, reference being had to the accompanying drawings forming a part of this specification wherein like reference characters designate corresponding parts in the several views.

Fig. 1 is a fragmentary sectional elevation illustrating a portion of a multi-cylinder engine.

Fig. 2 is a fragmentary sectional elevation illustrating a portion of the driving mechanism for 25 the rotatable valve or valves of the engine.

Fig. 3 is a section taken substantially through lines 3—3 of Fig. 1 looking in the direction of the arrows.

Fig. 4 is a fragmentary sectional view taken 30 substantially through lines 4—4 of Fig. 1 looking in the direction of the arrows.

Fig. 5 is a fragmentary sectional elevation illustrating another embodiment of the present invention.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The present invention is especially applicable to engines of the class having rotatable valves, preferably but not necessarily rotating continuously in one direction, for controlling the intake and firing of the fuel charge and for exhausting the products of combustion. In the illustrated embodiment of the invention, exemplifying one desirable adaptation thereof, a rotatable valve of the frusto-conical type is mounted in the cylinder head and is formed with substantially all or 50 at least the major portion of the combustion

chamber. The valve or rotor is formed with an opening or port in the side of the valve adapted to register with intake and exhaust passages and an ignition device during operation, there being an opening or port at the inner end or bottom of the rotor communicating at all times with the cylinder.

In the drawings I have illustrated, by way of example, certain embodiments of the invention as applied to an internal combustion engine of the spark ignition type. However, it will be understood that the invention is not limited to an engine in which combustion is initiated by spark ignition. For most uses the engine is of the multi-cylinder type but for the purposes of simplification a single cylinder unit of the engine is illustrated in the present embodiment, it being understood that the remaining cylinders and associated parts are identical to the structure herein shown and described.

Referring to the drawings, the present engine comprises a cylinder 20 within which a suitable piston 21 is mounted for reciprocation. The piston is connected in the usual manner through a wrist pin 21a and connecting rod 22 to the crank-shaft 23 of the engine. Surrounding the cylinder 20 is a cylindrical jacket 24 which is rigidly secured to the crankcase or forms substantially an integral portion of the crankcase. This jacket member 24 has an extended portion spaced from the wall of the cylinder 20 to provide a water cooling space or chamber 25 extending entirely around the cylinder. The lower or inner end of the cylinder 20 is formed with an annular rib 20a forming a pilot portion slidable into and having a smooth fit within the inner cylindrical wall of the lower section 24a of the jacket member 24, the rib 20a carrying sealing rings 26 to prevent leakage of the coolant between the juxtaposed surfaces of the portions 20a and 24a.

The engine is provided with a cylinder head 27 which is cast with a depending wall or skirt 28 terminating adjacent the outer end of the cylinder and spaced therefrom to provide a liquid cooling space or chamber 29 adapted to form a continuation of the chamber 25. When the cylinder head is assembled the lower edge of the skirt or jacket portion 28 is drawn down tightly against the upper thickened edge 24b of the jacket member 24, there being a gasket 30 interposed between the juxtaposed surfaces of these portions adapted to be compressed to provide a liquid tight joint.

In the embodiment of Fig. 1 the outer end of the cylinder is formed with an outwardly extending annular flange 20b extending in juxtaposed relation to an annular wall portion 31 of the cylinder head. The annular flange 20b of the cylinder is formed with an annular recess 32 at its inner side forming a vertical shoulder or abutment 33. The lower edge of the wall portion 31 of the cylinder head is formed with an annular rib 34 which fits into the recess 32 and abuts against the shoulder 33. The upstanding annular portion of the flange 20b, which surrounds the annular rib 34 of the cylinder head and which has the vertical shoulder 33 engaging this rib 34, forms in effect an expansion control ring adapted, during operation, to restrain outward expansion of the wall portion 31 relative to the cylinder. A gasket 35 is interposed between the adjacent surfaces of the portions 20b and 31. This gasket may be of the copper-asbestos type capable of sustaining high temperatures and pressure, and when the cylinder head is drawn down tightly

this gasket will provide a liquid and gas tight joint.

The cylinder head is formed with a series of lugs or ribs 36 and 37 bored to receive bolts 38 extending from bosses (not shown) on the jacket member 24 which, as stated, is fixed to the crankcase. The cylinder head may be drawn down tightly to the crankcase or jacket 24 by suitable nuts applied to the upper ends of the bolts 38, thus connecting the jackets 24 and 28 tightly together at the water tight joint formed by the gasket 30. The upper end of the jacket 24 is formed with an inwardly projecting boss 39 providing a ledge adapted to support the flange 20b of the cylinder 20. This boss 39 at its upper edge is provided with a series of ducts 39a providing communication between the outer chamber 29 and the chamber 25 for the flow of coolant between these chambers. The boss is also cut away at intervals at 39b to provide additional communicating passages between the chambers 25 and 29. Thus, the cylinder 20 is positioned with respect to the jacket 24 by means of its flange 20b overlying the supporting boss 39 and engaging the upper edge thereof, as shown particularly in Fig. 4. It will, therefore, be seen that when the cylinder head is drawn down tightly through the medium of the bolts 38 the gasket 35 will be compressed to provide a water tight joint and the rib-like portion 34 of the wall 31 of the cylinder head will fit snugly within the recess 32.

The cylinder head is formed with a generally frusto-conical recess 40 within which is mounted a rotatable valve or rotor 41 which is also of generally frusto-conical construction having tapering outwardly converging walls corresponding generally in shape to the inner walls of the recess 40. The bottom or inner wall 41a of the valve is preferably tapered so as to correspond substantially to the taper of the piston head, the construction being such that the piston head will approach very closely the bottom of the valve 41 when the piston is at the outer end of its stroke.

The valve member 41 is formed with a side port 43 communicating with the combustion chamber 42 and adapted to register successively during rotation of the valve with a spark plug 44, an exhaust passage or conduit 45, and an intake conduit or passage 46 in the cylinder head, the direction of rotation of the valve being indicated by the arrow in Fig. 3. As also shown in this figure, the liquid coolant chamber 29 has extensions 29a in the cylinder head extending substantially around the valve member 41 and also extending along and in the height of the outer walls of the exhaust and intake passages 45 and 46. Another portion 29b of the coolant chamber extends through the dividing wall between these passages. From this construction it will be seen that substantially all portions of the cylinder, cylinder head, valve and intake and exhaust passages, which are subjected to heating during operation, are exposed to the cooling effect of the liquid circulated through the water jackets. The coolant is preferably introduced into the lower end of the chamber 25, circulated upwardly through the communicating chambers, which have a common outlet in the cylinder head.

In addition to the side port 43 the valve 41 has a central port or opening 47 at its inner end communicating with the cylinder. The valve member 41 is also formed with a cooling chamber 48 extending entirely around the combustion chamber of the valve member. This cooling

chamber is adapted to receive any suitable cooling medium such, for example, as metallic sodium, which is sealed into the chamber by means of an expanding plug 48a.

In the present embodiment the valve or rotor 41 is driven at one-half engine or crankshaft speed. It is provided with a projecting stem 49 through the medium of which the driving mechanism for the valve is connected. The valve housing portion 39 of the cylinder head is provided with an annular recess 50 in its outer end through which the valve stem 49 extends. Within this recess is located a cup-shaped spring retainer member 51 adapted to receive a compression spring 52 surrounding the valve stem 49. The outer end of the spring engages a steel coupling disk 53. This disk is formed centrally thereof with an annular set of teeth 54 meshing with corresponding teeth formed on the end of the valve stem 49. The valve stem is tapped to receive a threaded stud or bolt 56 which carries a nut 56a engageable with the coupling disk 53 and adapted to be tightened to draw down the disk and maintain its teeth 54 in constant mesh with the teeth on the outer end of the valve stem. The spring 52 is, therefore, held under constant compression so as to yieldingly hold the valve upwardly within the frusto-conical recess 40 in the valve housing. The strength of this spring and the amount of preloading thereof is such that the effort exerted by the spring to raise the valve within the valve housing is sufficient to substantially offset or equal the effort exerted during the suction stroke of the piston to draw the valve downwardly and away from its seat.

The coupling disk 53 is provided with external teeth 55 meshing with internal teeth 57a on a ring gear 57. This gear in turn has external teeth 57b meshing with the teeth of a valve driving gear 58 secured to a longitudinally extending top shaft 61. The cylinder head is formed with a housing 59 provided with a removable closure 60 for housing the driving mechanism located in the cylinder head. The top shaft 61 at one end thereof carries a gear 62 meshing with a gear 63 secured to the upper end of a tower shaft 64. This tower shaft extends through a tube or housing 65 and carries at its lower end a gear 66 meshing with a gear 67 secured to the crankshaft 23 of the engine.

It will be noted that the bottom of the valve member 41 has a downwardly and outwardly tapering contour 41a corresponding to the tapering contour of the piston head. This tapering bottom portion 41a of the valve terminates at a point inward of the outer end of the cylinder wall in an outwardly and upwardly tapering or bevelled portion 68 which overlies the bevelled end 69 of the cylinder wall. A clearance of a few thousandths of an inch is at all times maintained between the bevelled or tapering bottom portion 68 of the valve and the bevelled end 69 of the cylinder wall so that at no time during operation will the valve contact the end of the cylinder. This clearance will be maintained even during the suction stroke of the piston since, as previously stated, the loading of the spring 52 is sufficient to counteract the downward pull on the valve during the suction stroke. The valve member is also preferably provided with an exterior relief area 70 extending entirely around the valve and substantially the height of the side port 43. This annular relief area may be formed either in the valve or in the

wall 40 of the valve housing and may be constructed and serve the purposes in accordance with copending application Serial No. 495,260.

The embodiment illustrated in Fig. 5 differs from the preceding embodiment in that the joint between the walls of the cylinder jacket 24 and the cylinder head jacket 28 lies below the wrist pin 21a when the piston 21 is at its extreme outer position within the cylinder 20. In this embodiment the cylinder head jacket 28 has a depending skirt 71 which terminates well below the outer end of the cylinder. The jacket 24 is, therefore, shortened as compared with its construction in Fig. 1 and a sealing gasket 72 is interposed between the meeting edges of these jackets and at a point below the wrist pin 21a. The jacket member 24 is provided with an inwardly projecting annular flange 73 providing a seat for a sleeve 74 surrounding the outer end of the cylinder and spaced therefrom to provide a chamber 75 for liquid coolant. The sleeve 74 is also spaced from the jacket portion 71 so as to provide a chamber 76 for liquid coolant. The chamber 75 is in constant communication with the chamber 25 through the medium of ducts or passages 77, and the chamber 76 is in constant communication with the chamber 75 through the medium of transverse slots or ducts 78 similar to the ducts 39a illustrated in Fig. 4.

From the foregoing construction it will be seen that the cylinder flange 20b is supported upon the projecting sleeve or flange 73 of the fixed jacket 24 through the medium of the sleeve 74, the latter providing communication at all times between the chamber 75 and the associated cooling chambers 76 and 25. By virtue of the construction illustrated in Fig. 5 it is possible in overhauling the engine to remove the piston without disconnecting it from the crankshaft. The construction in this embodiment permits the cylinder head and cylinder to be removed relatively to the jacket 24 without disturbing the piston, after which the pin 21a may be withdrawn to permit removal of the piston. Other than the foregoing the construction of the engine in the embodiment of Fig. 5 corresponds substantially to that previously described.

It will be seen that the present invention provides a very accurate control of the expansion rates of the cylinder head valve housing 31 and rotatable valve 41. This valve housing and also the piston cylinder are surrounded by a jacket within which a liquid coolant is circulated, thus providing substantially uniform dissipation of heat. In preferred practice the cylinder head (including the valve housing) is made of an aluminum alloy whereas the rotary valve and the cylinder are formed of suitable ferrous alloys. Hence, the valve housing will have a greater rate of expansion than either the valve or cylinder, the latter two having substantially the same rate of expansion. Ordinarily, therefore, the head will tend to expand more rapidly or to a greater degree than the valve, thus increasing the clearances between the valve and valve housing which will have the undesirable result of causing oil leakage especially during the suction stroke of the piston. However, in accordance with the present invention the valve housing has an annular rib seated in the recess 32 of the cylinder and abutting against the shoulder 33. This shoulder acts as a restraining abutment preventing outward movement of the valve housing relative to the cylinder. Hence, a constant control over the expansion of the housing with relation

to the cylinder and valve is maintained and the desired operating clearances between the valve and valve housing are held substantially uniform during operation. Much improved operation is, therefore, achieved while reducing materially the oil consumption.

I claim:

1. In an internal combustion engine, a cylinder, a cylinder head having a portion provided with a generally frusto-conical cavity, a generally frusto-conical valve in said cavity, said cylinder and valve being formed of ferrous metal and said cylinder head being formed of metal having a greater coefficient of thermal expansion, and means on the cylinder engaging said head for restraining lateral expansion of said head at the locality of its bearing engagement with the valve at the inner end of the latter.

2. In an internal combustion engine, a cylinder, a cylinder head having a portion provided with a generally frusto-conical cavity, a generally frusto-conical valve in said cavity, said cylinder and valve being formed of ferrous metal and said cylinder head being formed of metal having a greater coefficient of thermal expansion, and annular means on said cylinder engaging said head for restraining lateral expansion of said head at the locality of its bearing engagement with the valve at the inner end of the latter.

3. In an internal combustion engine, a cylinder, a cylinder head having a portion provided with a generally frusto-conical cavity, a generally frusto-conical valve in said cavity, said cylinder and valve being formed of ferrous metal and said cylinder head being formed of metal having a greater coefficient of thermal expansion, and an abutment ring on said cylinder engaging the head adjacent the locality of its bearing engagement with the inner end of the valve for restraining lateral expansion of the head.

4. In an internal combustion engine, a cylinder, a cylinder head having a portion provided with a generally frusto-conical cavity, a generally frusto-conical valve in said cavity, said cylinder and valve being formed of ferrous metal and said cylinder head being formed of metal having a greater coefficient of thermal expansion, and means controlled by the cylinder engaging said head for maintaining the expansion rate of the head adjacent the inner end of the valve substantially corresponding to that of the valve.

5. In an internal combustion engine, a cylinder, a cylinder head having a portion provided with a generally frusto-conical cavity, a generally frusto-conical valve in said cavity, said cylinder and valve being formed of ferrous metal and said cylinder head being formed of metal having a greater coefficient of thermal expansion, and abutment means controlled by the cylinder for restraining any substantial lateral expansion of the inner wall portion of said cavity relatively to the adjacent portions of the valve, said abutment means comprising an annular shoulder on the outer end of the cylinder abutting against an annular portion of the head fitting within said shoulder.

6. In an internal combustion engine, a cylinder, a cylinder head having a portion provided with a generally frusto-conical cavity, a generally frusto-conical valve in said cavity, said cylinder head being formed of metal having a greater coefficient of thermal expansion than the metal of said cylinder and valve, and an abutment ring on said cylinder engaging the head adjacent the locality of its bearing engagement with the

inner end of the valve for restraining lateral expansion of the head.

7. In an internal combustion engine, a cylinder, a cylinder head having a portion provided with a generally frusto-conical cavity, a generally frusto-conical valve in said cavity, said cylinder head being formed of metal having a greater coefficient of thermal expansion than the metal of said cylinder and valve, and means controlled by the cylinder and abutting said head for maintaining the expansion rate of the head adjacent the inner end of the valve substantially corresponding to that of the valve.

8. In an internal combustion engine, a cylinder, a cylinder head having a portion provided with a generally frusto-conical cavity, a generally frusto-conical valve in said cavity, said cylinder head being formed of metal having a greater coefficient of thermal expansion than the metal of said cylinder and valve, and abutment means controlled by the cylinder for restraining any substantial lateral expansion of the inner wall portion of said cavity relatively to the adjacent portions of the valve.

9. In an internal combustion engine, a cylinder, a cylinder head, a rotatable valve in said head, a liquid cooling jacket surrounding the cylinder, a second liquid cooling jacket on the head surrounding said valve, outwardly projecting flange means on the cylinder terminating in spaced relation to said second jacket, projecting means on the first named jacket underlying said flange means at a distance therebelow, a member interposed between said projecting means and flange means for supporting the cylinder on said first named jacket, sealing means between said flange means and the cylinder head, sealing means between said jackets, and means for drawing down the head upon said cylinder and first named jacket to compress said sealing means.

10. In an internal combustion engine, a cylinder head having a generally frusto-conical cavity, a generally frusto-conical rotatable valve in said cavity, said head comprising spaced outer and inner walls extending around the valve providing a liquid cooling chamber, a cylinder, a jacket surrounding the cylinder providing a liquid cooling chamber communicating with the first named chamber with the outer end of the jacket in sealing engagement with the inner end of said outer wall, the outer end of the cylinder and the inner end of said inner wall having abutting means adjacent the inner end of the valve for restraining lateral expansion of the head adjacent the inner end of the valve, said abutting means being separated from said outer wall by said first named cooling chamber.

11. In an internal combustion engine, a cylinder head having a generally frusto-conical cavity, a generally frusto-conical rotatable valve in said cavity, said head comprising spaced outer and inner walls extending around the valve providing a liquid cooling chamber, a cylinder, a jacket surrounding the cylinder providing a liquid cooling chamber communicating with the first named chamber with the outer end of the jacket in sealing engagement with the inner end of said outer wall, the inner end of said inner wall having an annular recess and the outer end of the cylinder having an annular abutment fitting into said recess and exposed to the cooling liquid in said first chamber and also providing means for restraining lateral expansion of the head adjacent the inner end of the valve.

12. In an internal combustion engine, a cylin-

der head having a generally frusto-conical cavity, a generally frusto-conical rotatable valve in said cavity, said head comprising spaced outer and inner walls extending around the valve providing a liquid cooling chamber, a cylinder, a jacket surrounding the cylinder providing a liquid cooling chamber communicating with the first named chamber with the outer end of the jacket in sealing engagement with the inner end of said outer wall, the inner end of said inner wall having an annular recess around the outside thereof and the outer end of the cylinder having an annular abutment fitting into said recess opposite the inner end of the valve and separated from said outer wall by said first named cooling chamber.

13. In an internal combustion engine, a cylinder head having a generally frusto-conical cavity, a generally frusto-conical rotatable valve in said cavity, said head comprising spaced outer and inner walls extending around the valve providing a liquid cooling chamber, a cylinder having a lesser coefficient of thermal expansion than said cylinder head, a jacket surrounding the cylinder providing a liquid cooling chamber communicating with the first named chamber with the outer end of the jacket in sealing engagement with the inner end of said outer wall, the outer end of the cylinder and the inner end of said inner wall having abutting means adjacent the inner end of the valve for restraining lateral expansion of the head adjacent the inner end of the valve, said abutting means being separated from said outer wall by said first named cooling chamber.

14. In an internal combustion engine, a cylinder head having a generally frusto-conical cavity, a generally frusto-conical rotatable valve in said cavity, said head comprising spaced outer and inner walls extending around the valve providing a liquid cooling chamber, a cylinder having a lesser coefficient of thermal expansion than said cylinder head, a jacket surrounding the cylinder providing a liquid cooling chamber communicating with the first named chamber with the outer end of the jacket in sealing engagement with the inner end of said outer wall, the inner end of said inner wall having an annular recess and the outer end of the cylinder having an annular abutment fitting into said recess and exposed to the cooling liquid in said first chamber and also providing means for restraining lateral expansion of the head adjacent the inner end of the valve.

15. In an internal combustion engine, a cylinder, a cylinder head having a portion provided with a generally frusto-conical cavity, a generally frusto-conical valve in said cavity, said cylinder and valve being formed of ferrous metal and said cylinder head being formed of metal having a greater coefficient of thermal expansion, abutting means interposed between the cylinder and head for restraining lateral expansion of said head at the locality of its bearing engagement with

the valve at the inner end of the latter, and a liquid cooling chamber in the head within which said restraining means is exposed to cooling fluid.

5 16. In an internal combustion engine, a cylinder, a cylinder head having a portion provided with a generally frusto-conical cavity, a generally frusto-conical valve in said cavity, said cylinder and valve being formed of ferrous metal and
10 said cylinder head being formed of metal having a greater coefficient of thermal expansion, means on said cylinder engaging the head adjacent the inner end of said cavity for restraining lateral expansion of said head at the locality of its bearing engagement with the valve at the inner end of the latter, and a liquid cooling chamber in the head within which said restraining means is exposed to cooling fluid.

17. In an internal combustion engine, a cylinder, a cylinder head having a portion provided with a generally frusto-conical cavity, a generally frusto-conical valve in said cavity, said cylinder and valve being formed of ferrous metal and said cylinder head being formed of metal having a greater coefficient of thermal expansion, an abutment ring on said cylinder engaging the head adjacent the locality of its bearing engagement with the inner end of the valve for restraining lateral expansion of the head, and a liquid cooling chamber in the head within which said abutment ring is exposed to cooling fluid.

18. In an internal combustion engine, a cylinder, a cylinder head having a portion provided with a generally frusto-conical cavity, a generally frusto-conical valve in said cavity, said cylinder and valve being formed of ferrous metal and said cylinder head being formed of metal having a greater coefficient of thermal expansion, abutment means controlled by the cylinder for restraining any substantial lateral expansion of the inner wall portion of said cavity relatively to the adjacent portions of the valve, said abutment means comprising an annular shoulder on the outer end of the cylinder abutting against an annular portion of the head fitting within said shoulder, and a liquid cooling chamber in the head within which said shoulder is exposed to cooling fluid.

19. In an internal combustion engine, a cylinder, a cylinder head having a portion provided with a generally frusto-conical cavity, a generally frusto-conical valve in said cavity, said cylinder head being formed of metal having a greater coefficient of thermal expansion than the metal of said cylinder and valve, an abutment ring on said cylinder engaging the head adjacent the locality of its bearing engagement with the inner end of the valve for restraining lateral expansion of the head, and a liquid cooling chamber in the head within which said abutment ring is exposed to cooling fluid.

CLARENCE E. FRANK.
